UNITED STATES PATENT OFFICE.

ARTHUR E. PEARCE, OF ASHTABULA, OHIO.

DESIGN FOR A TIRE.

53,971.

Specification for Design.

Patented Oct. 14, 1919.

Application filed October 30, 1917. Serial No. 199,381. Term of patent 14 years.

To all whom it may concern:

Be it known that I, ARTHUR E. PEARCE, a citizen of the United States, residing at Ashtabula, in the county of Ashtabula and State of Ohio, have invented a new, original, and ornamental Design for a Tire, of which the following is a specification, reference being had to the accompanying drawing, forming part thereof.

Figure 1 of the drawing is a fragmental top plan showing my new design applied to the tread portion of a tire, and,

Fig. 2 is a transverse section through the tire.

I claim:

The ornamental design for a tire, as shown.

ARTHUR E. PEARCE.
